[73] Assignee: Mobil Oil Corporation, New York, N.Y.

[57] CLAIM

The ornamental design for a hinged lid food container or the like, substantially as shown.

DESCRIPTION

FIG. 1 is a perspective view of a hinged lid food container or the like in an open position showing our new design;

FIG. 2 is a front elevational view thereof in a closed position;

FIG. 3 is an end elevational view thereof in a closed position;

FIG. 4 is a rear elevational view thereof in a closed position;

FIG. 5 is a bottom view thereof showing the container in an open position.
